ELECTRIC TUNNEL KILN

Edward Van der Pyl, Holden, Mass., assignor to
 Norton Company, Worcester, Mass., a corpora-
 tion of Massachusetts

Application December 28, 1948, Serial No. 67,633

15 Claims. (Cl. 13—20)

1

The invention relates to tunnel kilns.

One object of the invention is to provide a tunnel kiln of high production per unit mass of kiln, that is to say capable of vitrifying more pounds of ware per day per ton of kiln than previous tunnel kilns. Another object of the invention is to provide a very compact tunnel kiln capable of vitrifying a relatively large mass of ware, as represented by many unit pieces, for a given floor space occupied by the kiln. Another object of the invention is to vitrify a comparatively large mass of ware for each kilowatt hour of energy used. Another object of the invention is to provide a tunnel kiln of low capital investment compared to its productive capacity, that is to say to obtain a greater mass of total ware vitrified per year for every hundred dollars invested in the kiln than heretofore possible. Another object of the invention is to provide a tunnel kiln which will produce a greater mass of total ware vitrified per man hour of labor than hitherto practicable.

Another object of the invention is to provide means for ready access to the interior of a tunnel kiln in order to straighten out a jam or smash. Another object of the invention is to provide a tunnel kiln with a plurality of parallel tunnels and an efficient charging mechanism for automatically ramming ware into the several tunnels seriatim. Another object of the invention is to provide various controls and interlocks to render the charging mechanism as foolproof as possible. Another object of the invention is to provide a tunnel kiln of the character indicated in which the only manual labor required is to place bats with "green" ware on a loading conveyor and remove bats with fired ware from a discharging conveyor or a table located adjacent thereto.

Other objects will be in part obvious or in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings, in which are shown two of various possible embodiments of the mechanical features of the invention,

Figure 1 is a side elevation on a smaller scale as compared with most of the remainder of the drawings, of a tunnel kiln constructed in accordance with this invention.

Figure 2 is a side elevation on a larger scale

2

than Figure 1 of a table to which the ware is transferred by the discharging conveyor of the kiln.

Figure 3 is an end elevation of the loading or entrance end of the kiln proper on a larger scale than Figure 1.

Figure 4 is an end elevation of the exit or discharging end of the kiln proper on the same scale as Figure 3.

Figure 5 is a side elevation on a still larger scale of the loading or charging mechanism at the entrance end of the kiln including the loading conveyor.

Figure 6 is a vertical sectional view taken on the line 6—6 of Figure 5.

Figure 7 is a central vertical longitudinal sectional view of the kiln proper showing the tunnels therein and including the preheating zone, the firing zone, and a portion of the annealing zone, this view being on a larger scale than that of Figure 1 but on a smaller scale than that of Figures 3 and 4.

Figure 8 is a vertical cross sectional view taken on the line 8—8 of Figure 7.

Figure 9 is a central vertical longitudinal sectional view similar to Figure 7 and on the scale thereof, illustrating the remainder of the inside of the kiln proper including the tunnels and showing the remainder of the annealing zone.

Figure 10 is a vertical cross sectional view taken on the line 10—10 of Figure 9.

Figure 11 is a vertical sectional view taken on the line 11—11 of Figure 9.

Figure 12 is a vertical sectional view taken on the line 12—12 of Figure 7.

Figure 13 is a vertical sectional view taken on the line 13—13 of Figure 7 but on a larger scale.

Figure 14 is a vertical sectional view taken on the line 14—14 of Figure 7 and on the same scale as Figure 13.

Figure 15 is a fluid pressure diagram.

Figure 16 is a sectional view of a solenoid and relay switch.

Figure 17 is the wiring diagram.

Figure 18 is a plan view of the loading conveyor and rams.

Figure 19 is a vertical sectional view on an enlarged scale showing a batt on the loading conveyor actuating a limit switch.

Figure 20 is cross sectional view on an enlarged scale of the discharging conveyors at the exit end of the kiln.

Figure 21 is a view similar to Figure 1 of a modification of the invention.

Figure 22 is an elevation of the front of the kiln of Figure 21 on a larger scale.

Figure 23 is an elevation of the rear or exit end of the kiln of Figure 21 on the same scale as Figure 22.

Figure 24 is a vertical longitudinal sectional view in the axis plane of the first half of the kiln of Figure 21, on a larger scale than Figure 21.

Figure 25 is a view similar to Figure 24 showing the second half of the kiln.

Figures 26 and 27 are cross sectional views taken respectively on the lines 26—26 and 27—27 of Figure 24 but on a larger scale than Figure 24.

Figure 28 is an addition to the wiring diagram of Figure 17.

Figure 29 is a vertical sectional view through the elevator for the kiln of Figure 21, the section being taken on the line 29—29 of Figure 30.

Figure 30 is a plan view of the elevator for the kiln of Figure 21.

The sectional views, Figures 8, 10, 11, 12, 13 and 14, are nearly vertical sectional views but not quite since the long dimension of the kiln is slightly inclined to the horizontal, as shown being at about 2° to the horizontal, and the sections are taken parallel to the faces of the bricks which are at right angles to the bottom of the kiln.

Referring first to Figures 1, 3, 4, 7, 8 and 9 to 14, the refractory kiln structure may be supported and enclosed in a rectangular parallelepipedal box having side walls 21 and 22 a bottom 23 a top 24 and end walls 25 and 26. All of these walls including the top and the bottom may be made out of steel plate and may be secured together by welding and may be strengthened by braces such as the angle irons 27 shown in Figure 1, including some angle iron braces 28 which are continued to form legs 29. The top 24 is preferably made of a large number of pieces of steel plate supported by angle irons 30 welded to the sides 21 and 22 at the top as well shown in Figures 13 and 14. Preferably the various sections of the top 24 are removable in order that, in the case of a bad smash, the brick work may be removed to make repairs. However, most of the time it will be sufficient to use the easy means of obtaining access to the tunnels as hereinafter described.

Referring now especially to Figures 13 and 14, resting on the bottom 23 is a course of bricks 35 which extends from end to end of the kiln. The upper surface of this course of bricks 35 is a plane surface but slightly inclined to the horizontal since the bottom 23 is slightly inclined to the horizontal as clearly shown and as already stated. Resting on the marginal bricks of the course 35 on either side of the kiln and located at a short distance from the walls 21 and 22 respectively are walls 36 of courses of bricks each wall 36 having an inside surface which is in a vertical plane and an outside surface which is in a vertical plane. Adjacent the walls 36 and resting upon the courses of bricks 35 are long courses of bricks 37 extending from end to end of the kiln.

This tunnel kiln has a preheating zone, a firing zone and an annealing zone. It has two tunnels 40 and 41 each of which extends right through the kiln from the preheating zone through the firing zone and the annealing zone. These tunnels 40 and 41 are connected to each other by a passage 42 in the firing zone but otherwise they are separated from each other. Figure 8, which shows a cross section through the annealing zone,

is also typical of the preheating zone. Figures 13 and 14 are cross sections through the firing zone. I will now describe the remainder of the refractory structure at the preheating and annealing zones by reference to Figure 8 and thereafter will describe the remainder of the refractory structure in the firing zone by reference to Figures 13 and 14.

Extending between the long courses of bricks 37 in the preheating and annealing zones are wide bricks 45 which are substantially rectangular parallelepipeds but have grooves in their top edges to receive long refractory pieces 47 which support rods 48 upon which slide batts 49 supporting pieces of ware such as grinding wheels 50 being vitrified. The bricks 45 completely fill the space between the courses 37 and above the courses 35 to form a bottom to the tunnel 40. It will be seen that the bricks of the courses 37 and the wide bricks 45 and the long refractory pieces 47 which fit in grooves in the top edges of the bricks 45 together form a plane surface except for long grooves in the pieces 47 in which the rods 48 rest. Upon this plane surface rest many tunnel forming bricks 55 which are generally of inverted U-shape but as shown are wider than they are high and have thick legs. These bricks all together form a tunnel ceiling 58 and the upper portions of the sidewalls of the tunnel 40 are inclined as shown at 59. The roof 60 of the tunnel 40 forms the floor of the tunnel 41 which is further formed by tunnel forming bricks 65 which, like the bricks 55, extend from a wall 36 on one side to the wall 36 on the other side. As will be seen, the tops of the bricks 55 collectively form a plane except that there are grooves for the support of long refractory pieces 47. The tunnel forming bricks 65 are similar to the tunnel forming bricks 55 except that the upper bricks 65 need have no grooves in their top surfaces. Thus the upper tunnel 41 has a tunnel ceiling 68 and the upper portions of the sidewalls of the tunnel 41 are inclined as shown at 69. On the long refractory pieces 47 for the upper tunnel 41 are rods 48 supporting batts 49 supporting ware such as grinding wheels 50 being vitrified.

The structure thus far described constitutes a refractory structure forming the two tunnels 40 and 41, but I preferably provide additional bricks over the bricks 65 to form a thick roof for the tunnel 41 for heat insulation. For example, I may provide long courses of bricks 71 like the courses 37 resting upon the bricks 65 adjacent to the walls 36 and fill the space between these courses 71 with wide rectangular parallel epipedal bricks 72 as shown. Then on top of the plane formed by the tops of the walls 36, of the courses 71 and of the bricks 72, I may lay flatwise long bricks 75 in a plurality of courses. These long bricks 75 may be of the same dimensions and arrangement as the long courses of bricks 35, the former forming the top of the refractory structure and the latter forming the bottom of the refractory structure. A full comprehension of this entire refractory structure is readily gained from the foregoing description taken in connection with Figures 7 and 9 as well as Figure 8.

Referring now to Figures 13 and 14 which represent the firing zone, the refractory structure of the kiln is in many respects the same as that already described. The courses of bricks 35 form the bottom of the structure and the long bricks 75 75 form the top of the structure. The walls 36

are a continuation of the same walls in the other zones and adjacent them on the bricks 88 are the long courses of bricks 87 and under the long bricks 75 adjacent the walls 36 are the long courses of bricks 71. Between these long courses of bricks 71 are the wide bricks 72. But in place of the wide bricks 45 are tunnel floor bricks 80 having rectangular depressions 81 to lower the floor of the tunnel 40 and in place of the tunnel forming bricks 55 are tunnel forming bricks 85 in pairs with a wide space between them forming the passage 42 instead of a ceiling 68. The tunnel 40, however, has inclined upper portions of the side wall 69. Similarly, instead of the tunnel forming bricks 65, the firing zone has tunnel forming bricks 86 similar to the bricks 85. The bricks 85 are cut away to support the long refractory pieces 47 for the tunnel 41. Between courses of bricks 86 is a long rectangular space 87 which may be of the same width as that of the passage 42 which is also rectangular but may be of slightly lesser height as shown. The ceiling of the tunnel 41 is therefore formed by the bricks 72. The bricks 80 as well as the bricks 85 are cut away to provide space for the long refractory pieces 47. These refractory pieces 47 support, in grooves therein as shown, long rods 48 upon which rest the batts 49 supporting grinding wheels 50 being vitrified. When the kiln is in operation there is, in each tunnel 40 and 41, a pair of continuous parallel sets of rods 48 and these support continuous contiguous sets of batts 49 constituting two long trains of batts and each train is moved at intervals as will later be described.

Referring now to Figures 7 and 13, extending through the side walls 21 and 22 and into the walls 36 are short refractory tubes 90 located at three levels with respect to the major axis of the kiln. On the lower level resistor rods 91 extend through these tubes 90 and from the tubes 90 at the side wall 21 to the tubes 90 at the side wall 22 as clearly shown. These resistor rods 91 pass through the walls 36 and through the tunnel floor bricks 80 under the long refractory pieces 47 and across the rectangular depressions 81 in the lower tunnel 40. At the middle level resistor rods 91 extend through the tubes 90 and from the tubes at the side wall 21 to the tubes 90 at the side wall 22 and through the walls 36 and through the tunnel forming bricks 85 across the passage 42. At the upper level resistor rods 91 extend through the tubes 90 and from the tubes 90 at the side wall 21 to the tubes 90 at the side wall 22 and through the walls 36 and through the tunnel forming bricks 86 and across the long rectangular space 87 of the upper tunnel 41.

These resistor rods 91 are electrical resistors and while any refractory resistor rod capable of being heated to a high enough temperature for the purpose and having a reasonable life at such temperature may be used, the best type of resistor rod now known to me and one which is thoroughly satisfactory for use in this kiln is a recrystallized silicon carbide resistor rod having cold ends now well known to the art. During operation of the kiln all of these resistor rods 91 are connected to electrical power desirably controlled by automatic electrical controlling apparatus to maintain the current flow in them severally to the required amperage to heat them severally to temperatures sufficient to maintain the desired temperature in the firing zone of both tunnels 40 and 41. Such electrical controlling apparatus is available on the market and

need not be described herein. However it may be noted that during operation those portions of the rods 91 extending across the depressions 81 and across the passage 42 and across the space 87 respectively are customarily heated to temperatures above 1200° C. and some of them are at times as hot as 1400° C. Preferably the cold ends of the rods 91 extend on each side from their ends all the way through the various bricks 10 right to the spaces constituting depressions 81, the passage 42 and the space 87.

Referring now to Figure 14, on two levels the lower one of which is between the rods 91 of the lower level and the rods 91 of the middle level and the upper one of which is between the rods 91 of the middle level and the rods 91 of the upper level are short refractory tubes 100 extending through the side walls 21 and 22 and into the walls 36. On the lower of these levels extending through the tubes 100 and through the walls 36 and the bricks 85 into the tunnel 40 as shown are pyrometers 101. These of course are refractory tubes containing wires of different metals to form a thermocouple at the end of the tube and as will be clearly seen they measure the temperature of the tunnel 40 close to the ware being vitrified, that is close to the grinding wheel 50. Similarly on the upper of these two levels extending through the tubes 100 are more pyrometers 101 and this upper bank of pyrometers extends into the upper tunnel 41 adjacent the grinding wheels 50, passing through the walls 36 and through the bricks 86. The middle bank of resistor rods 91 is controlled by the electrical controlling apparatus and the pyrometers 101, alternately an upper and lower pyrometer 101 for successive resistor rods 91 of the middle bank. Additionally, voltage drop across each bank of rods 91 is separately controllable manually. These measures suffice to keep both tunnels 40 and 41 at predetermined temperatures. These tunnels per se are of course connected but the batts 49 in the upper tunnel 41 form a separating plane when the kiln is in operation and hence it is important to be able to regulate the upper bank of resistor rods 91 separately from the lower bank of resistor rods 91. As shown in Figure 7, there are many resistor rods in the three banks on the three levels described, eighteen being shown in each bank but there need be only a few pyrometers, for example three in each bank at the firing zone but pyrometers 101 are located at intervals all through the kiln in two banks one for each tunnel as more clearly shown in Figures 1, 7 and 9.

Referring now to Figure 7, preferably the tunnel bricks of one kind change gradually into tunnel bricks of another kind. For example the wide bricks 45 gradually change into the tunnel floor bricks 80 so as to form in the preheating zone a gradual dropping of the bottom of the tunnel 40 by a gentle decline 102 and a gradual rise of the bottom of the tunnel 40 at the start of the annealing zone in a somewhat steeper upward inclination 103. The tunnel forming bricks 65 of the upper tunnel 41 change a little bit more abruptly into the parallelepipedal bricks 72 to form tapered boundaries 104 and 105 of the roof of the upper tunnel. Likewise the passage 42 has tapered boundaries 106, 107, 108 and 109 at its ends.

The foregoing shaping of the boundaries of the tunnels is streamlining, which is desirable because there is a gentle flow of air through the tunnels 40 and 41 when the kiln is in operation, induced by the incline of the kiln and the chim-

nay to be described. The pressure drop involved in this flow has been found to be, as measured in the chimney, from .025 inch to .035 inch of water.

The kiln is provided with various flues and dampers such as the dampers 113 and 114, Figure 7, to control the temperature in the various zones and also to permit gases from the burning of any temporary binder in the wheels 50 to escape. Referring now to Figure 1, a chimney pipe 115 is connected to a long pipe 116 on top of the kiln. As shown in Figure 12, at the entrance end of the kiln the bricks 45 are cut and so are the bricks 37 and the walls 36 and before the rest of the bricks are laid, a flue structure 117 made of refractory metal such as a nickel-iron-chromium alloy of 60 nickel, 24 iron and 16 chromium is inserted in place and the remainder of the bricks are cut to fit around and in the flue structure 117 as shown by Figure 12. This flue structure 117 has a bottom horizontal passage 118 opening into the bottom of the tunnel 40, a couple of horizontal passages 119 opening from vertical passages 120 into the sides of the tunnel 40 and the vertical passages 120 are continued upwardly to the long pipe 116. The vertical passages 120 are also connected to the bottom horizontal passage 118 so that the vertical passages 120, one on each side as clearly shown in Figure 12, take care of both sides and the bottom of the tunnel 40. The flue structure 117 likewise has a bottom horizontal passage 128 connected to the bottom of the tunnel 41 and a pair of short horizontal passages 129 connecting vertical passage 130 to the sides of the tunnel 41 which likewise extend upwardly to the large pipe 116 and the bottom horizontal passages 128 are connected to the vertical passages 130 and thus these vertical passages 130 take care of the bottom and sides of the tunnel 41. To show this construction as clearly as possible, Figure 12 is a broken line section on the line 12-12 of Figure 7 and in Figure 7 the brick work in front of the structure forming the vertical passages 120 and 130 has been removed more clearly to show the shape of this flue structure 117.

Referring now to Figures 9 and 10, a flue structure 137 is connected to the overhead pipe 116 and again the brick work is cut away somewhat to accommodate this structure 137 all as shown in these two figures. This flue structure 137 however has two pipes 140 on the outside of the kiln, these pipes 140 being connected to the long pipe 116 and extending horizontally and then vertically downward along the sides of the kiln to form an inverted U-shaped structure. Between the legs of the U extend flattened pipes 141, 142, 143 and 144, reading from bottom to top. The pipe 141 opens into the bottom of the tunnel 40, the pipe 142 opens into the top of the tunnel 40, the pipe 143 opens into the bottom of the tunnel 41 and the pipe 144 opens into the top of the tunnel 41. As shown in Figure 9, the bricks 45 are mitred to form depressions with inclined boundaries 145 above the pipes 141 and similarly the bricks 55 are mitred to form depressions with inclined boundaries 146 above the pipes 143 to permit an even flow of the air into those pipes. As shown in Figure 1, there are dampers 151, 152, 153 and 154 for the pipes 141, 142, 143 and 144 respectively. There are such dampers 151, 152, 153, and 154 on both sides of the kiln.

Referring now to Figure 11, I provide special removable bricks 158 and 159 and the steel side walls 21 and 22 are cut away so that these bricks 158 and 159 extend to the outside of the furnace

and they are provided with rings, not shown, whereby they can readily be withdrawn to gain access to the tunnels 40 and 41 respectively. These bricks 158 and 159 may be shaped as shown having a slight taper for ready removal and of course the other bricks are cut away to provide the exact space in which these bricks 158 and 159 fit.

Referring now to Figure 1, at the loading end of the kiln I provide a loading conveyor 160 and at the exit end of the kiln I provide a discharging conveyor 161. I further preferably provide as shown in Figure 2 a receiving table 162. The loading conveyor 160 has one pair of endless V-belts 163 intermittently driven by a motor 164 while the discharging conveyor 161 has two pairs of endless sprocket chains 165 and 166, and both pairs 165 and 166 are continuously driven by a motor 167. The sprocket chains 165 are at the level of the discharge end of the tunnel 40 while the sprocket chains 166 are at the level of the discharging end of the tunnel 41. The table 162 has freely rotatable rollers 168 at the same level as the sprocket chains 165 and has freely rotatable rollers 169 at the level of the sprocket chains 166. Consequently whenever a batt emerges from either tunnel, it is promptly moved out of the way and upon the table 162 unless this is too crowded with batts whereupon it simply remains at or near the far end of the discharging conveyor 161.

Referring now to Figures 1 and 5, I provide an elevator 170 to transfer batts 49 from the conveyor 160 to a position in front of the tunnel 40 during a given half cycle of kiln operation and to a position in front of the tunnel 41 during the next half cycle of kiln operation. This elevator 170 is connected by a piston rod 171 to a piston 172 in a cylinder 173. Batts are periodically pushed into the tunnels 40 and 41 respectively by means of rams 174 and 175 and referring now to Figure 15, the lower ram 174 is connected by a piston rod 176 to a piston 177 and a cylinder 178 while the upper ram 175 is connected by a piston rod 179 to a piston 180 in a cylinder 181.

It will be convenient to describe the cycle of operation of the kiln before describing the elevator 170, conveyor 160, conveyor 161 and table 162 in detail, and preparatory to describing the cycle of operation I shall, with special reference to Figure 17, identify the solenoids, relays, limit switches and other electrical apparatus. Three phase power can be used to operate the mechanism and is identified by the three lines 185. From two of these lines 185 extend wires 186 and 187 to the primary coil of a step-down transformer 188. The secondary of the transformer 188 is connected to main operating lines identified as L1 and L2. The interval between the start of each cycle is determined by an adjustable timer 190 which is diagrammatically represented in Figure 17. From L1 a wire 191 extends to a wire 192 which is connected to one terminal 193 of the timer 190. From L2 extends a wire 194 which is connected to a terminal 195 of the timer. The third terminal 196 of the timer 190 is connected by a wire 197 to one end of a relay 198 for the motor 164 of the loading conveyor 160 while the other end of this relay 198 is connected to the wire 192. When the relay 198 is energized, three relay switches 199 close and connect the three lines 185 to the motor 164 to operate it.

Closed by the elevator 170 whenever it is in its lowermost position is a limit switch LS1. Operated by the elevator 170 just before it comes

to the level of the lower ram 174 is a limit switch LS2. Operated by the elevator 170 just before it comes to the level of the upper ram 175 is a limit switch LS2a. Operated by a batt 49 on the loading conveyor 160 when the batt has been moved as far as it will go to the right, Figure 5, is a limit switch LS3. Operated by a batt 49 as it leaves the lower tunnel 40 at the discharging end of the kiln is a limit switch LS4. Operated by a batt 49 as it leaves the tunnel 41 at the discharging end of the kiln is a limit switch LS4a. Operated by the lower ram 174 when it has moved all the way forward that is toward the kiln, is a limit switch LS5. Operated by the upper ram 175 when it has moved all the way forward that is toward the kiln is a limit switch LS5a. Operated by the lower ram 174 when it is fully retracted is a limit switch LS6. Operated by the upper ram 175 when it is fully retracted is a limit switch LS6a. For causing the elevator 170 to rise, a solenoid 200 is energized. For causing the elevator 170 to stop at the station of the lower tunnel 40, a solenoid 201 is energized. This operates a latch 202 which will be explained hereinafter. For causing the lower ram 174 to advance, a solenoid 203 is energized. For causing the upper ram 175 to be advanced, a solenoid 204 is energized. The electrical mechanism further includes a relay R1 and a relay R2.

The timer 190 is diagrammatically illustrated in Figure 17 and any timer operating upon the general principle of the timer 190 may be employed. Timers are now made by a number of manufacturers and are readily available upon the market. The mechanism is shown as mounted upon a panel 210. The terminal 193 which is always connected to the power line L1 is connected by a wire 211 to a solenoid 212, the other terminal of which is connected by a wire 213 to a terminal of a solenoid 214, the other terminal of which is connected to a main timer terminal 215 which can be called the reset terminal because at the close of the cycle of operation the wire 216 which leads to the terminal 215 is connected through to line L2.

Also connected to the power terminal 193 of the timer is a wire 217 which is connected to one terminal of a motor 218, the other terminal of which is connected by a wire 219 to a switch terminal 220 opposite a switch terminal 221. The switch terminal 221 is connected by a wire 222 to the power terminal 195 of the timer.

A switch terminal 225 of the timer is connected by a wire 226 to the wire 222. A switch terminal 227 opposite the switch terminal 225 is connected by a wire 228 to the third terminal 196 of the timer which is a load terminal. While the timer is running a contactor 230 connects the terminals 220 and 221. When the timer times out a contactor 231 connects the terminals 225 and 227. In Figure 17 the timer parts are shown in timing position.

The motor 218 drives a pinion gear 232 and this may be driven at reduced speed for there may be a reduction gearing not shown in the casing of the motor 218. The pinion gear 232 drives a large gear 233 journaled on a stud 234 projecting from a lever 235. Likewise projecting from the lever 235 are studs 236 and 237 and a shaft 238. Secured to the large gear 233 is a pinion gear 240 which meshes with a large gear 241 journaled on the stud 238. Secured to the large gear 241 is a pinion gear 242 which meshes with a large gear 243 journaled on the stud 237. Secured to the large gear 243 is a

pinion gear 244 which meshes with a large gear 245 that is secured to the shaft 238. A clock spring 250 shown in dotted lines in Figure 17 is on the far side of the lever 235 and the inner end of this clock spring 250 is secured to the shaft 238 while the outer end is secured to a pin 251 projecting rearwardly from the lever 235.

The lever 235 is pivotally mounted on a stud 252 and has a forked left end 253 to which is connected a link 254 by means of a pin 255. A pin 256 connects the link 254 to a core member 257 of the solenoid 214. When the solenoid 214 is energized, the gear 233 is drawn into engagement with the pinion 232 and the gearing slowly rotates the final gear 245 but when the solenoid 214 is deenergized, a spring 258 connected to the pin 255 and to a pin 259 projecting from the panel 210 lifts the lever 235 thus disengaging the gear 233 from the pinion 232 and then the clock spring 250 resets the timer.

Projecting from the front face of the gear 245 is a cam 260. When the timer times out this cam 260 engages a detent 261 of a bell crank lever 262 mounted on a stud 263 projecting from the panel 210. On the lower end of the bell crank lever 262 is formed a latch 264 which, while the timer is timing, holds a hook 265 on the upper end of a rod 266 which extends downwardly through a guide 267 and is connected to a core member 268 of the solenoid 212. A spring 269 supported by a bracket 270 secured to the panel 210 tries to hold the bell crank lever 262 against a stop 271 also secured to the panel 210. A spring 272 extending from the guide 267 presses against a collar 273 on the rod 266 and therefore tries to hold the rod 266 in its upper position but the solenoid 212 is more powerful than the spring 272. While the latch 264 engages the hook 265, the rod 266 cannot descend even though the solenoid 212 is energized but when the cam 260 hits the detent 261 the latch 264 is withdrawn from the hook 265 and the rod 266 will go down if the solenoid 212 is energized. The reset position of the timer is determined by a stop block 275 secured to a member not shown which is rotatable on the same axis as that of the shaft 238 and which can be secured in adjusted position to fix the time interval measured by the timer. This stop block 275 is in the path of the cam 260 and when the clock spring 250 resets the timer, the cam 260 moves clockwise until it hits the block 275. By adjusting the block 275 angularly the time interval can be set from a few seconds to many minutes.

As shown in Figure 17, the timer is running and since the contactor 230 connects the terminals 220 and 221 the motor 218 is running. The two solenoids 212 and 214 are connected in series as shown and they are energized since the terminal 193 is always live and the wire 216 is at this time connected to line L2. Finally the cam 260 hits the detent 261 which releases the rod 266 which opens the circuit between terminals 220 and 221 thus stopping the motor 218. At the same time the contactor 231 connects the terminals 225 and 227 so current flows from line L1 to line L2 through the loading conveyor motor relay 198 as follows: from L1 to wire 191 to wire 192 to relay 198 to wire 197 to timer load terminal 196 to wire 228 to switch terminal 227 through contactor 231 to switch terminal 225 to wire 226 to wire 222 to timer terminal 195 to wire 194 to line L2. Accordingly the relay switches 199 are closed and the motor 164 starts. This causes the

V-belts 163 to move and finally a batt 49 strikes limit switch LS3.

The limit switch LS3 is a double switch having a normally closed contactor 278 and a normally open contactor 279 which are mechanically connected. Engagement by a batt with the actuator of LS3 opens contactor 278 and closes contactor 279. When the batt leaves the actuator the contactors return to the position shown in Figure 17. The contactor 179 when closed connects wires 281 and 282. Line L1 is connected to the relay R1 as shown in Figure 17 and the other side of R1 is connected by a wire 283 to the wire 281. The wire 282 is connected to a wire 284 which is connected by a wire 285 to a wire 286 which is connected to a normally closed contactor 287 of limit switch LS4 which is a double switch and is operated by a batt 49 leaving the tunnel 40. Contact 287 is connected by a wire 288 to the limit switch LS4a which is operated by a batt 49 when it leaves the tunnel 41. The limit switch LS4a is likewise a double switch having a normally closed contactor 289. The wire 288 is connected by this contactor 289 to a wire 290 which is connected to line L2. Accordingly when the batt 49 hits LS3 the relay R1 is energized. This action causes a contactor 291 to connect a wire 292 leading from L2 to a wire 293 leading to the elevator solenoid 200, the other end of which is always connected by a wire 294 to the wire 191 which is always connected to L1. Therefore the elevator 170 starts upwardly.

Another function performed by the limit switch LS3 is to stop the loading conveyor 164 and also to reset the timer 190. In order to understand this I will now describe the reset circuit for the timer. Energy flows from L1 through wire 191 to wire 192 to terminal 193 to wire 211 through solenoid 212 to wire 213 through solenoid 214 to terminal 215 to wire 216 through closed limit switch LS6a to wire 295 through closed limit switch LS6 to wire 296 through closed limit switch LS1 to wire 297 through the contactor 278 of LS3 to wire 284 to wire 285 to the closed contactor 287 of LS4 to wire 288 through the closed contactor 289 of LS4a to wire 290 to the line L2. Opening of the contactor 278 of LS3 breaks this circuit so the solenoids 212 and 214 go dead, the spring 258 raises the arm 235 and the clock spring 250 resets the timer. Also at the same time the spring 272 raises the rod 266 and the latch 264 re-engages the hook 265. The contactor 231 is now up and the terminals 225 and 227 are no longer connected so the relay 198 goes dead and the relay switches 199 open and the motor 164 stops. Although as soon as the batt 49 on the elevator 170 moves upwardly the contactor 278 again connects wires 297 and 284, the circuit remains broken because the slightest upward movement of the elevator 170 opens the limit switch LS1 this switch being held closed when the elevator 170 is down. Switch LS1 is a normally open limit switch but while the timer 190 is timing, it is held closed by the elevator 170 in a manner to be hereinafter more fully described.

In Figure 17 the circuits are shown while the timer is timing and in such condition that the elevator 170 will move to its upper position so that a batt 49 will be rammed into the upper tunnel 41. Although as soon as the elevator 170 starts to rise the contactor 279 of LS3 opens, the relay R1 does not go dead because a holding circuit for it has been established as follows. From line L1 to the relay R1 then to wire 283 and through a contactor 300 to the wire 284 to

wire 285 to wire 286 through the contactor 287 to wire 288 through the contactor 289 to wire 290 to line L2. As the elevator 170 rises it closes the normally open limit switch LS2 but nothing happens and the switch LS2 immediately re-opens. Finally when the elevator 170 arrives at its top position it closes the limit switch LS2a and this energizes the upper ram solenoid 204 in the following manner: from line L1 to wire 191 to wire 301 through solenoid 204 to wire 302 through LS2a to wire 303 through a contactor 304 of the relay R2 to wire 305 to wire 306 through contactor 291 of relay R1 to wire 292 to line L2. Now, with the elevator 170 still held up by fluid pressure, the upper ram 175 pushes a batt 49 into the upper tunnel 41 and consequently another batt 49 must emerge from the exit end of the tunnel 41 onto the always moving sprocket chains 166. The emerging batt moves out onto the rollers 169 but before it gets there it actuates the limit switch LS4a and opens the contactor 289 and closes a contactor 310. This momentary opening of the contactor 289 opens the holding circuit of the relay R1 provided the upper ram 175 had completed its forward stroke. For there is an alternate path from the wire 288 to the wire 290 by way of a wire 311, a wire 312 and the limit switch LS5a which is a normally closed limit switch and opens when the ram 175 is fully forward. This circuit is provided so that the elevator 170 will not descend unless an incoming batt is rammed the full distance into the kiln. But with the limit switch LS5a open the moment the contactor 289 opens, the holding circuit of relay R1 is definitely broken so the contactor 291 disconnects the wires 292 and 293, the solenoid 200 is deenergized and the elevator 170 starts down. This movement soon opens the limit switch LS2a which breaks the circuit to the upper ram solenoid 204 thus causing the upper ram 175 to retract.

Momentary closing of the contactor 310 energized the relay R2 but before describing the circuits I shall describe this relay R2 which is a special kind of a relay.

The relay R2 is an Allen-Bradley 700 type BM-20 relay of the permanent magnet type. Unlike mechanically held relays, this type BM employs no latches or other holding devices. The operating coil of the relay is divided into two parts, one for closing and the other for opening the relay. When the closing section of the coil is energized, the plunger is drawn upwardly. This relay has pole faces and at the end of the upward movement they meet and an auxiliary switch in the circuit of the closing coil is opened. This auxiliary switch is so designed that the tiny arc which it forms interrupts the circuit at the instant of maximum magnetization of the operating magnet. Therefore a strong magnetic flux remains in the magnetic circuit and the hardened steel plunger becomes a permanent magnet, holding the relay in closed position. The flux is not dissipated until the opening section of the operating coil is energized whereupon the alternating current demagnetizes the plunger which moves to its lowermost position. The position of parts with all the contactors up and the plunger up is referred to as the closed position of the relay while the position in which the contactors and plunger are down is referred to as the open position of the relay. Figure 17 shows this relay in open position.

When the contactor 310 closes, the relay R2 is closed. The circuit is as follows: from line L1

to a wire 315 to the relay R2, then through the relay this being the closing circuit, then by a wire 316 through a contactor 317 of the relay R2 which is closed when the relay is open, then by way of a wire 318 and through the contactor 310 to the wire 290 to the line L2. This closes the relay R2.

When the upper ram 175 has been fully retracted the limit switch LS6a which is a normally open limit switch is closed. The lower ram 174 not having moved the limit switch LS6 remains closed this also being a normally open limit switch which is closed when the lower ram 174 is fully retracted. These switches LS6a and LS6 are shown as closed in Figure 17 because they are closed when the timer is timing and all switches are shown in the position which they then occupy except that the relay R2 is shown in its first position, that is to say open, it having either position when the timer is timing depending upon which tunnel the next batt is to enter. When the elevator 170 reaches the bottom the switch LS1 is closed this also being a normally open limit switch. The contactor 278 of LS3 is now closed because there is no batt in contact with the switch LS3. The contactor 281 of limit switch LS4 is closed and so is the contactor 289 of limit switch LS4a. Consequently the solenoids 212 and 214 of the timer 190 are reenergized and the timer 190 starts timing again. Eventually it times out by the cam 260 striking the detent 261 pulling the latch 264 away from the hook 265 which stops the motor 218 and closes the contactor 231 to connect the power from line L2 to the loading conveyor motor relay 198, the circuit being L2, 194, 195, 222, 226, 225, 231, 221, 228, 196, 197, 198, 192, 191 and L1. Now the loading conveyor 160 moves a batt 49 against the limit switch LS3 again. This opens the contactor 278 which opens the circuit to the solenoids 212 and 214. The timer resets and the contactor 231 moves upwardly breaking the circuit to the motor relay 198 so the loading conveyor 160 stops. The contactor 279 closes and this energizes the relay R1 which is held energized by the holding circuit through the contactor 300. Again the elevator solenoid 200 is energized which starts the elevator 170 upwardly a second time.

When the relay R1 closed, the elevator latch solenoid 201 was energized moving the latch 202 into a position where it will hold the elevator 170 in line with the lower tunnel 40. This circuit is as follows: from line L1 by way of wire 315 to a wire 320 through solenoid 201 to a wire 321 across a contactor 322, now closed, of relay R2 to the wire 305 to wire 306 through contactor 291 to wire 292 to line L2.

Accordingly the elevator 170 rises only to a position in front of the lower ram 174 where it stops. In doing so it closes the limit switch LS2 which, like the limit switch LS2a, is a normally open switch. Closing of the switch LS2 energizes the lower ram solenoid 203 by the following circuit: from line L1 to wire 191 to wire 301 to a wire 325 through the solenoid 203 to a wire 326 through LS2 to a wire 327 through a contactor 328 which is now closed, to wire 306 through contactor 291 to wire 292 to line L2. Accordingly the lower ram 174 moves forward and rams a new batt 49 into the lower tunnel 40. This causes a batt with a vitrified wheel 50 to emerge from the exit end of the tunnel 40 onto the always moving sprocket chains 165. These chains 165 carry the batt to the rollers 168 and in the course of so doing

the batt actuates the limit switch LS4. This causes the contactor 287 to break the circuit between the wires 286 and 288 which deenergizes the relay R1 if the alternate circuit through the limit switch LS5 is open. The limit switch LS5 is a normally closed limit switch the same as the limit switch LS5a and it is opened only when the lower ram 174 has moved to its extreme forward position. The alternate circuit is from wire 285 to limit switch LS5 to wire 311 to wire 312 through LS5a to wire 290 and then to line L2 or 285, LS5, 311, 289, 290, L2. If there is no casualty and there usually is not, LS5 and contactor 287 will be open at the same instant and this breaks the holding circuit through the contactor 300 of the relay R1 which therefore goes dead and the solenoid 200 is deenergized. Therefore the elevator 170 goes down and since this opens the limit switch LS2 the lower ram solenoid 203 is deenergized and the lower ram 174 retreats closing the limit switch LS6.

Actuation of the limit switch LS4 also causes a contactor 330 thereof to close. This sends current through the relay R2 as follows: from line L1 to wire 315 to relay R2 to a wire 331 through a now closed contactor 332 to a wire 333 through contactor 330 to a wire 334 to line L2. This circuit is the opening circuit of the relay R2 and accordingly the relay opens putting the parts in the position shown in Figure 17 again. When the ram 174 has moved all the way back and when the elevator 170 has moved all the way down, the switches LS6 and LS1 are closed, the switch LS6a was already closed, the contactors 287 and 289 are now closed, so the circuit is completed through the relays 212 and 214 and the timer 190 starts timing again.

This double cycle of operation continues over and over again indefinitely so long as the batts are supplied to the loading conveyor 160. At any one time a number of batts spaced a short distance apart may be placed upon the loading conveyor 160 and they will be fed into the kiln automatically at given intervals of time as determined by the setting of the timer 190. These batts will alternately go into the tunnel 41 and the tunnel 40 and since two tunnels are working all the time, this kiln can vitrify twice as much ware in a given period of time as a similar kiln of about the same size having only one tunnel.

In case the description of the relay R2 be considered too meager, it is noted that there are many relays on the market controlled by three wires which place the contactors in two positions. Mechanically held relays are an example and Figure 16 is a diagrammatic illustration of a mechanically held relay R2a which can be substituted for the relay R2 to achieve the same purpose. This relay R2a, the solenoid and operating parts of which are shown in section, is connected to the wires 316, 315 and 331 as shown. It has a solenoid coil 340 one end of which is connected to the wire 316, the other end of which is connected to the wire 331 and the middle of which is connected to the wire 315. That part of the coil between the wires 316 and 315 is the closing part of the coil while that part of the coil between the wires 315 and 331 is the opening part of the coil. The relay R2a has a solenoid core 341 made of iron connected to a long rod 342 made of brass or other non-magnetic material. The rod 342 has welded or otherwise secured thereto a block 343 having a pair of depressions 344 and 345. The rod 342 and the

block 343 are slidably held in a casing 346 having an opening 347 across which extends a bar 348. A detent 349 extends through a hole in the bar 348 and is pressed toward the block 343 by a spring 350. When current flows between the wires 315 and 316 the core 341 is drawn to the left to cause the detent 349 to engage the depression 345. When current flows between the wires 315 and 331 the core 341 is drawn to the right to cause the detent 349 to engage the depression 344 as shown in Figure 16. The various wires extending to the operating contacts of the relay and the contactors which open and close the circuits are the same as in the case of the relay R2 and are diagrammatically illustrated in Figure 16. Relays of this type have spring held contactors but this is a detail of electrical engineering which it is not necessary for me to illustrate since it belongs to the art of switches and is well understood. A relay of this type which can readily be used for the relay R2 is disclosed in U. S. Letters Patent No. 2,057,380 to Lincoln M. Keefe patented October 13, 1936.

The manner in which the solenoid 200 controls the elevator 170, the manner in which the solenoid 203 controls the lower ram 174, and the manner in which the solenoid 204 controls the upper ram 175 are disclosed in Figure 15. A pipe 355 is connected to a source of fluid under pressure and I have found that it is quite practical and convenient to use the city water supply assuming the water is supplied at at least moderately high pressure. A pipe 356 is connected to exhaust, for example to the sewer since the amount of water used in operating this apparatus is small. The pipe 355 is connected to an inlet port 357 of a valve 358 having a valve plunger 359 with lands 360 and 361. The pipe 356 is connected to a port 362 of the valve 358 which port 362 is connected by a passage 363 to the end of the valve 358 beyond and outside of the land 360 and by a passage 364 to the end of the valve 358 beyond and outside of the land 361. The port 357 is always connected to the space between the lands 360 and 361. A port 365 is sometimes connected to the space between the lands 360 and 361 and is sometimes connected to the space beyond and outside of the land 361 while a port 366 is sometimes connected to the space outside and beyond the land 360 and sometimes connected to the space between the lands 360 and 361.

Similarly, an inlet port 367 connects the pressure pipe 355 to a valve 368 having a valve plunger 369 having a land 370 and a land 371 and the exhaust pipe 356 is connected to a port 372 leading to passages 373 and 374 and the valve 368 has ports 375 and 376. Similarly, the pressure pipe 355 is connected to an inlet port 377 of a valve 378 having valve plunger 379 having a land 380 and a land 381 and the exhaust pipe 356 is connected to a port 382 leading to passages 383 and 384 and the valve 378 has ports 385 and 386. The valves 358, 368 and 378 may be identical and are so shown. The solenoid 200 controls the valve 358, the solenoid 203 controls the valve 368, and the solenoid 204 controls the valve 378. Whenever the solenoid 200 is de-energized, a spring 390 holds the valve plunger 359 in the position shown in which position pressure is connected to the port 365 and the port 366 is connected to exhaust. Whenever the solenoid 200 is energized, the plunger 359 is drawn to the left, Figure 15, and pressure is

connected to the port 366 and the port 365 is connected to exhaust.

A spring 391 holds the plunger 369 in the position shown in Figure 15 whenever the solenoid 203 is deenergized and in this position of the plunger 369 the port 375 is connected to pressure while the port 376 is connected to exhaust. But when the solenoid 203 is energized the valve plunger 369 is drawn upwardly, Figure 15, and then the port 376 is connected to pressure and the port 375 is connected to exhaust. Similarly, a spring 392 holds the plunger 379 in the position shown in Figure 15 whenever the solenoid 204 is deenergized and in such position the port 385 is connected to pressure and the port 386 is connected to exhaust. But when the solenoid 204 is energized, the plunger 379 is drawn upwardly, Figure 15, and then the port 386 is connected to pressure and the port 385 is connected to exhaust.

The port 365 is connected to the upper end of the cylinder 173 by means of a pipe 395 and a shunting pipe 396. The port 366 is connected to the lower end of the cylinder 173 by means of a pipe 397 and a shunting pipe 398. In the pipe 395 between the ends of the shunting pipe 396 is a throttle valve 399. In the shunting pipe 396 is a check valve 400 and the direction in which the liquid can flow is indicated by the arrow. In the pipe 397 between the ends of the shunting pipe 398 is a pressure regulating valve of the constant pressure outlet type 401 and also in the pipe 397 between the ends of the shunting pipe 398 is a check valve 402 and the direction in which the liquid can flow is indicated by the arrow. In the shunting pipe 398 is a throttle valve 403 and a check valve 404.

The port 375 is connected to the front end of the ram cylinder 178 by means of a pipe 405 and a shunting pipe 406. The port 376 is connected to the rear end of the cylinder 178 by means of a pipe 407. In the pipe 405 between the ends of the shunting pipe 406 is a throttle valve 408. In the shunting pipe 406 is a check valve 409 and the direction in which the liquid can flow is indicated by an arrow. In the pipe 407 is a throttle valve 410.

The port 385 is connected to the front end of the ram cylinder 181 by means of a pipe 415 and a shunting pipe 416. The port 386 is connected to the rear end of the cylinder 181 by means of a pipe 417. In the pipe 415 between the ends of the shunting pipe 416 is a throttle valve 418. In the shunting pipe 416 is a check valve 419 and the direction in which the liquid can flow is indicated by the arrow. In the pipe 417 is a throttle valve 420.

It will now be seen that when pressure is connected to the port 365, as is the case when the parts are in the position shown in Figure 15, the elevator 170 goes down or stays down. Also when the pressure is connected to the port 366 the elevator 170 goes up or stays up. It is clear that when the solenoid 200 is deenergized pressure will be connected to the port 365 and when the solenoid 200 is energized pressure will be connected to the port 366. When the elevator 170 is moving upwardly, the fluid has to flow through the check valve 402 because it cannot flow through the check valve 404. Hence, when the elevator is rising, the valve 401 insures a constant pressure on the piston 172. However, should the load be lighter than usual, the elevator cannot rise at too fast a speed because the exhaust from the cylinder 173 has to go out through

the throttle valve 399 being unable to pass through the check valve 400. So these valves 401 and 399 give adjustable control of the upward movement of the elevator 170 and provide for a smooth steady rise. When the elevator 170 is descending, fluid can flow through the check valve 400, but it also has to flow through the throttle valve 403 and so the speed of descent can be regulated.

In the case of the rams, the forward motion is under the control of both of the throttle valves 408 and 410 for the ram 174 and 418 and 420 for the ram 175. Rearward movement of these rams is, however, only under the control of the throttle valve 410 for the ram 174 and 420 for the ram 175. Accordingly the valves 410 and 420 can be set for fast movement of the ram, short of a runaway movement, while the valves 408 and 418 can be set for a rather slow movement of the rams to avoid any accident in ramming the batts into the tunnels.

Referring now to Figures 5 and 18, the motor 164 which drives the loading conveyor 160 has a built-in speed reduction gearing so that the sprocket gear 425 driven thereby rotates only at a moderate speed. This sprocket gear 425 drives a chain 426 which drives a sprocket gear 427 keyed to a jack shaft 428 having secured thereto a pair of pulleys 429 (only one shown) over which pass the V-belts 163. These V-belts 163 rest upon rollers 430 extending between angle iron frame members 431 which are supported by legs 432 and are also supported from the front legs 29 of the kiln. This conveyor 160 is preferably a long conveyor and it is shown as broken away in Figure 5 because of lack of space on the drawing but the portion left out is the same as the portion shown. The conveyor 160 has a number of legs 432 only one of which is shown in Figure 5. A great number of batts 49 may be placed upon the belts 163 of this loading conveyor 160 and the automatic mechanism already described will feed them one by one into the tunnels of the kiln, feeding them alternately into the upper tunnel 41 and the lower tunnel 40 and it is not necessary for the persons loading the kiln to space the batts apart in any regular or uniform manner provided only that the edges 435 having tongues and the edges 436 having grooves are crosswise of the belts 163 and that all the edges 435 are either in front or in back so that when the batts 49 are in a tunnel, each edge 435 will come against an edge 436 for interlocking of the batts in the tunnel. This interlocking serves to hold up a batt which may break in the tunnel.

The weight of the batts 49 on the loading conveyor 160 is taken by the rollers 430 and in order that the conveyor may operate smoothly and quietly, these rollers may be provided with ball bearings. The belts 163 are prevented from shifting laterally of the conveyor 160 by means of grooved pulleys 431 spaced at intervals along the conveyor 160. The belts 163 go out around a pair of idler pulleys 438 at the outer end of the conveyor 160, these idler pulleys 438 (only one shown) being mounted on a shaft 439 held between bearing supports 440 supported by brackets 441 secured to the outer legs 432. In their return courses, the belts 163 pass over a number of idler pulleys 442 rotatably held in position by brackets 443 depending from the frame members 431; a tensioning pulley 444 may be provided for each belt 163 these tensioning pulleys being rotatably mounted on arm 445 to

which are attached weights 446, the arms 445 being pivotally mounted on brackets 447 depending from the frame members 431. To prevent the batts 49 from moving off the belts 163 I preferably provide side guides 450 as shown in Figure 18. These side guides 450 are secured to the frame members 431 by means of brackets 451. These side guides 450 are not shown in Figure 5 since to do so would obscure the rest of the apparatus.

Referring now to Figures 5, 6 and 18, the elevator 170 may have the shape shown therein and it preferably has a pair of skid rods 455 upon which the batts 49 may slide the same as they slide upon the rods 48 in the tunnel. These skid rods 455 are preferably pitched at the same inclination to the horizontal as are the rods 48, all as indicated in Figure 1. The elevator 170 is secured to the piston rod 171 while the cylinder 173 has a head 456 under which is a large collar 457 which is secured to a support 458 that is fastened to the underside of the angle iron frame members 431.

Secured to the underside of the elevator 170 and extending downwardly therefrom as better shown in Figures 1 and 5 is a rod 460 having a notch 461 which is engaged by the latch 202 whenever the solenoid 201 is energized. As shown in Figure 5, the solenoid 201 has a core 462 which is connected by a link 463 to a bell crank lever 464 mounted on a stud 465 projecting from the timer panel 210 which is secured by a bracket 466 to one of the frame members 431 and also to an iron 467 extending between cross irons 468 secured to angle iron legs 469 that support the ram cylinders 178 and 181. One end of the bell crank lever 464 is in engagement with a rod 470 projecting from a cylindrical guide member 471 in a cylindrical casing 472 in which the guide member 471 slides. The latch 202 is secured to the guide member 471 and projects through a hole in the end plate 473 of the casing 472. A spring 474 is located in the casing 472 and extends between the end plate 473 and the guide member 471 normally to hold the latch 202 retracted and away from the rod 460; when however the solenoid 201 is energized, the core 462 is drawn downwardly, the bell crank lever 464 is rotated counter clockwise, the guide member 471 is urged to the right and the latch 202 will enter the notch 461 whenever the elevator 170 has risen far enough to bring the notch 461 opposite the latch 202 and this action stops the elevator 170 in the position where the ram 174 can push a batt 49 into the lower tunnel 40. But when the solenoid 201 is not energized as the elevator 170 moves upwardly, the elevator 170 moves all the way up to a position where the ram 175 can move a batt 49 into the upper tunnel 41.

Referring now to Figures 5 and 18, the cylinder 181 has bracket-shaped heads 476 and 477 which are secured to a plate 478 which is secured to channel irons 479 and 480. These channel irons 479 and 480 are secured to similar channel irons 481 and 482, and all four of the channel irons 479, 480, 481 and 482 are secured to the legs 469. The channel irons 479 and 481 make a pair and extend between a pair of legs 469 while the channel irons 480 and 482 make another pair and extend between the other pair of legs 469. All this is clearly indicated in Figure 5. Secured to the lower channel irons 481 and 482 is a plate 483, similar to the plate 478 and secured to this plate 483 are bracket-shaped heads 484 and 485

of the cylinder 178. Thus are the ram cylinders 178 and 181 held in the required position to ram batts into the tunnel 40 and the tunnel 41 respectively. The right hand pair of legs 469 have a further function in that they support flared guides 488 which serve to center the batts 49 over the elevator 170 as each batt 49 is brought into position over the elevator.

The general position of the discharging conveyor 161 is indicated in Figure 1 while its connection to the table 162 is indicated in Figure 2. The construction of the discharging conveyor 161 is, however, better shown in Figure 20. A pair of legs 490 (only one leg shown) is located close to the exit end of the kiln. Extending between these legs 490 are horizontal supporting angle irons 491 and 492. The angle iron 491 supports longitudinal horizontal angle irons 493 (only one shown). The angle iron 492 supports longitudinal horizontal angle irons 494. Journalled in brackets 495 (only one shown) secured to the angle irons 493 is a horizontal cross shaft 496 upon which are secured sprocket gears 497 (only one shown).

Journalled in brackets 500 (only one shown) secured to the angle irons 494 is a horizontal cross shaft 501 upon which are secured sprocket gears 502 (only one shown). Extending between the longitudinal irons 493 are cross members 503 (only one shown). Extending between the longitudinal irons 494 are cross members 504. Supported by the cross members 503 are chain supports 505 (only one shown). Supported by the cross members 504 are chain supports 506 (only one shown). The chains 165 ride on the supports 505 and the chains 166 ride upon the supports 506. Journalled in brackets 507 (only one shown) secured to the angle irons 494 is a horizontal cross shaft 508 upon which are secured sprocket gears 509 (only one shown). The chains 166 extend between the sprocket gears 502 and 509. The chains 165 extend between the sprocket gears 497 and sprocket gears not shown which are the same as the sprocket gears 509 and are mounted, journalled and driven in the same way. The lower sprocket gears corresponding to the sprocket gears 509 are mounted on a shaft 515 (Figure 1) which corresponds to the shaft 508. Secured to the shaft 515, as shown in Figure 1, is a pulley 516. Secured to the shaft 508 is a pulley 517. See also Figure 2. The motor 167 has speed reducing mechanism incorporated therein which drives a pulley 520 at slow speed and this pulley 520 drives a belt 521 which drives both of the pulleys 516 and 517. As previously stated, this motor 167 is running at all times when the kiln is in operation and hence the chains 165 and 166 are continually moving to remove from the discharge end of the kiln all batts which come out of the tunnels 40 and 41. As shown in Figure 2, the longitudinal horizontal angle irons 493 and 494 are extended and supported by legs 523 to form the receiving table 162 and between the irons 493 on the lower level extend the freely rotatable rollers 168, while between the irons 494 on the upper level extend the freely rotatable rollers 169. Batts 49 move out onto the rollers 168 and 169 from inertia, if there are no batts ahead of them and otherwise they are pushed out onto the rollers 168 and 169 by following batts driven by the chains 165 and 166. The rollers 168 and 169 are preferably journalled in ball bearings.

Referring now to Figure 3, the end front wall 25 of the kiln has secured thereto angle irons

526 forming guides for a door 527. This door 527 is a plate of iron having a cut-out 528 shaped like the cross section of the tunnels 40 and 41. It has lower level peep holes 529 for looking into the tunnel 40 and upper level peep holes 530 for looking into the tunnel 41. The peep holes 529 are ordinarily closed by swinging doors 531 pivotally mounted on pins 532. The peep holes 530 are normally closed by doors 533 pivotally mounted on pins 534. Any of the doors 531 or 533 may be moved out of closing position with a stick in order that the operator may see the inside of one of the tunnels.

Secured to the front of the door 527 below the cut-out 528 is a pair of horizontal angle irons 535. Secured to the elevator 170 as best shown in Figure 18 are lugs 536. When the elevator 170 moves upwardly to the level of the tunnel 40, the lugs 536 engage the angle irons 535 and lift the door 527 so that the cut-out 528 is aligned with the tunnel 40 permitting a batt to be rammed thereto. At other times this tunnel is closed at the front end by the door 527. When the elevator 170 goes downwardly the door 527 descends with the elevator. When the elevator 170 rises to the level of the upper tunnel 41, the lugs 536 engage the angle irons 535 and raise the door 527 so that the cut-out 528 is on a level with the upper tunnel 41, thus permitting a batt to be inserted thereto, and at other times the front end of the tunnel 41 is closed.

Referring now to Figure 4, secured to the end wall 23 at the rear or exit end of the kiln is a pair of angle irons 540 forming guides for a door 541 generally similar to the door 527. This door 541 has a cut-out 542 of the same shape as the cut-out 528. The door 541 has a wide rectangular slot 543 at the lower level and a wide rectangular slot 544 at the upper level. A door 545 has vertical slots 546 through which extend bolts having wing nuts 547. A door 548 has vertical slots 549 through which extend bolts having wing nuts 550. The doors 545 and 548 can be secured in any desired position over the wide slots 543 and 544 to let more or less air or none into the exit end of the kiln for regulating the temperatures of the annealing zones, and the slots 543 and 544 may also be used to view the tunnels.

Referring now to Figure 3, attached to the angle irons 535 are cables 551 which extend downwardly around pulleys 552 mounted on brackets 553 attached to the bottom 23 of the kiln at the front end thereof. These cables 551 run under the kiln bottom 23 the entire length thereof and referring now to Figure 4, the cables 551 extend around pulleys 554 mounted on brackets 555 secured to the bottom 23 of the kiln adjacent the exit end thereof. The cables 551 extend upwardly and over pulleys 556 journalled on studs 557 extending from the wall 23 near the top of the kiln and then the cables 551 extend downwardly and are attached to an angle iron 558 secured to the door 541. Thus whenever the door 527 rises to place the opening 528 in line with the tunnel 40 or 41, the door 541 rises to place the opening 542 in line with the tunnel 40 or 41. So whenever a batt can be rammed into a tunnel, another batt can emerge from the same tunnel. At other times, that is to say except when batts are entering and emerging from a tunnel, the tunnels are sealed by the doors 527 and 541.

Referring to Figure 5, the limit switch LS1 is shown attached by a bracket 560 to the panel 210

21.

holding its switch arm 561 in position to be engaged by an arm 562 secured to the elevator 170 so that whenever the elevator 170 is down, the limit switch LS1 is closed as already stated and when the elevator 170 rises the limit switch LS1 opens. Secured to the elevator 170 is an arm 563 which engages the arm 564 of the limit switch LS2 which is attached by a bracket 565 to a cross member 566 extending between the legs 469 near the kiln. The limit switch LS2a has a switch arm 568 which is engaged by the arm 562 secured to the elevator 170. The limit switch LS2a is attached by a bracket 570 to the plate 478.

Referring to Figure 19, I preferably provide a door jamb 571 secured to the underside of the front wall 25 of the kiln in order to hold the door 527 close to the wall 25 when the door 527 is down. Pivotally mounted on the door jamb 571 by means of a hinge 573 is a plate 574 engaging a roller 575 of the switch arm 576 of the limit switch LS3. The belts 163 carry a batt 49 against the plate 574 and this causes the plate 574 to move the switch arm 576 to the right, Figure 19, thus operating the limit switch LS3 with all the consequences previously described including the consequence of immediately stopping the belts 163. Preferably the motor 164 has an automatic brake as is supplied with many motors today so that whenever the power from the lines 185 is cut from the motor 164, it quickly stops without overrunning due to inertia. When the elevator 170 between the belts 163 raises the batt 49 above the plate 574, the spring 577 of the limit switch LS3 moves the arm 576 to the left and resets the limit switch LS3 to the position shown in Figure 17. At this point it may be noted that all of the limit switches are mechanically the same but this one LS3 is shown in a little more detail because the view is larger. However some of them are single action limit switches and some of them are double action limit switches all as previously pointed out in the description of the wiring with reference to Figure 17. The limit switch LS3 is secured in position by attachment to an angle iron 578 extending between the front legs 29 of the kiln.

Referring now to Figure 20, the limit switch LS4 is attached by means of a bracket 580 to the cross member 503 near the kiln. Also the limit switch LS4a is attached by a bracket 581 to the cross member 504 near the kiln. The limit switch LS4 has an arm 582 with a roller 583 and limit switch LS4a has an arm 584 with a roller 585. A batt emerging from the lower tunnel 40 engages the roller 583 and actuates the limit switch LS4 and later on releases it as the chains 165 carry the batt beyond the roller 583. Similarly a batt emerging from the tunnel 41 engages the roller 585 and actuates the limit switch LS4a and then the chains 166 carry the batt beyond the roller 585 allowing the limit switch LS4a to reset. The consequences of setting and resetting the limit switches LS4 and LS4a have already been fully described.

The operation of the limit switches LS5, LS5a, LS6 and LS6a is diagrammatically shown in Figure 15 and the mechanical arrangement is best shown in Figure 18 for the limit switches LS5a and LS6a and the mechanical details for the operation of the switches LS5 and LS6 are the same as in the case of LS5a and LS6a. Secured to the ram 174 and extending parallel to the axis of the cylinder 178 is a rod 590. Secured to the

22.

ram 175 and extending parallel to the axis of the cylinder 181 is a rod 591. The rod 591 is mounted to slide in bearings 592 and 593 extending upwardly from the plate 478. The rod 590 is mounted to slide in similar bearings, not shown, extending downwardly from the plate 483. The limit switches LS5a and LS6a are secured to the upper side of the plate 478 as shown in Figure 18 and similarly the limit switches LS5 and LS6 are secured to and extend downwardly from the plate 483. On the rod 591 is an adjustable dog 596 to actuate the limit switches LS5a and LS6a as shown in Figures 15 and 18. On the rod 590 is an adjustable dog 597 to actuate the limit switches LS5 and LS6. As already previously stated, the limit switches LS6 and LS6a are closed when their respective rams 174 and 175 are fully retracted but at other times they are open and the limit switches LS5 and LS5a are open when their respective rams 174 and 175 are fully forward, having completed the stroke to ram a batt into a tunnel, and otherwise they are closed. The ram 174 has headed studs 598 and the ram 175 has headed studs 599 which actually engage the batts during ramming. These studs are adjustable in order to square the batts as they are rammed into the tunnels.

A modification of the invention is illustrated in Figures 21 to 27 inclusive wherein, as best shown in Figures 24 and 25, the tunnels 40a and 41a are not connected. This kiln of Figures 24 to 27 has loading, conveying and discharging mechanism the same as already described for the kiln of Figure 1 with the proviso that since the tunnels 40a and 41a are spaced farther apart than are the tunnels 40 and 41, the rams 174 and 175 will be spaced farther apart and in line, of course, with the tunnels 40a and 41a and likewise the elevator 170 will rise a little higher to reach the level of the ram 175 so the cylinder 173 and the piston rod 171 should be a little longer. Also for the same reason the chains 165 and 166 will be farther apart vertically.

Referring now to Figure 24, this kiln has resistor rods 91 in banks on four levels instead of three levels, there being no resistor rods which serve to heat both tunnels as in the first described form of the invention. Thus there are two banks of rods 91 in the tunnel 40a one under the batts 49 and the other close to the tunnel ceiling in the firing zone and at a level practically the same as the ceiling of the other zones. The same is true in the case of the tunnel 41a which has two banks of resistor rods 91 one bank at a level below the batts 49 and the other bank just under the ceiling in the firing zone. In this form of the invention pyrometers 101 are located in the tunnels as clearly shown in Figures 24 and 25. The pyrometers 101 in the firing zone 60 of the tunnel 40a control the rods 91 in that tunnel and the pyrometers 101 in the tunnel 41a control the rods 91 in that tunnel. The other pyrometers give information to the kiln operator for adjustment of the dampers to maintain the 65 temperature gradients in the preheating zones and in the annealing zones as desired. The tunnels 40a and 41a are streamlined and the actual shapes of these tunnels are clearly shown in Figures 24 to 27 so further description would seem to be unnecessary. I will not describe the courses of bricks and the manner in which they are laid in the case of the kiln of this modification since the drawings are completely informative and the structure is similar to that already 70 described in the case of the kiln of Figure 1 and

one skilled in the art can readily construct the kiln of Figure 21 with drawings of Figures 24 to 27 before him. This kiln of Figure 21 has flattened pipes 140a forming a U-shaped structure (see Figure 21) and it has pipes 141a, 142a, 143a and 144a which in position and function are substantially the same as the pipes of the same numbers without the letter as already described, see Figure 25. Likewise this kiln has a bottom horizontal passage 118a, short horizontal passages 119a, a bottom horizontal passage 128a and short horizontal passages 129a similar to and for the same purpose as the passages of the same numbers without the letters and these are connected to vertical passages similar to the passages 120 and 130 which however are not shown in Figure 24. Likewise the kiln of Figure 21 has a long pipe 116a connected to a chimney 115a and connected to the pipes 140a and to passages like the passages 120 and 130 for the same purpose as already described, and the pipes and chimney of the kiln 21 may have dampers for controlling the flow of air and gases the same as already described for the kiln of Figure 1 so it is not necessary to illustrate these or further to describe them herein.

The tunnel doors for the modification of Figure 21 as shown in Figures 22 and 23 are mechanically similar to those already described but they differ in some details. Referring now to Figure 22, at the entrance end of the kiln are guides 526a guiding doors 527a and 527b having cut-outs 528a and 528b. The doors 527a have peep holes 529a and the doors 527b have peep holes 530a and these peep holes are respectively guarded by doors 531a and 533a. Horizontal angle irons 535a are secured to the door 527a and brackets 535b are secured to the door 527b. Connected to the angle irons 535a are cables 551a and connected to the brackets 535b are cables 551b.

Referring now to Figure 23, at the rear of the kiln are guides 540a and 540b guiding doors 541a and 541b. The door 541a has a wide rectangular slot 543a and the door 541b has a wide rectangular slot 543b and these slots are guarded by doors 545a and 548a which are so similar to the doors 545 and 548 that further description would seem to be superfluous. It will be noticed that in Figure 23 there is no cut-out corresponding to the cut-out 542 since the use of the two doors is equivalent.

The cables 551a pass around pulleys 552a and pulleys 554a and pulleys 556a and are secured to the door 541a. Similarly the cables 551b pass around pulleys 552b, around pulleys 554b and pulleys 556b and 556c and are attached to the door 541b.

Secured to the bottom of the door 527b is an angle iron 601. Secured to the elevator 170a as shown in Figure 30 is a lug 602. This lug 602 cannot operate the door 527a because when the elevator 170a goes up and down, it passes between the inner ends of the angle irons 535a. When, however, the elevator 170a rises high enough to place a batt 49 in front of the ram 175, the lug 602 engages the angle iron 601 and raises the door 527b which pulls the cables 551b and therefore also raises the door 541b. When the elevator 170a descends again the door 527b and the door 541b are dropped to the positions shown in Figures 22 and 23 where stops 604 secured to the end wall 25a hold the door 527b from dropping further and therefore the door 541b likewise can drop no further. The stops 604 engage

the angle iron 601 which projects from the face of the door 527b and the stops 604 do not interfere with the raising of the door 527a.

It will be remembered that, when the elevator 170 is about to rise only to the level of the ram 174, the solenoid 201 is energized by the wires 320 and 321. Referring now to Figure 28, I show therein an addition to the wiring diagram of Figure 16 wherein between the wires 320 and 321 is an additional pair of solenoids 605. Each of these solenoids 605 is connected by a wire 606 to the wire 320 and each of these solenoids 605 is connected by a wire 607 to the wire 321 so whenever the elevator latch solenoid 201 is energized, the pair of solenoids 605 is likewise energized. The elevator 170a is the same as the elevator 170 except that it has the central lug 602 instead of the pair of lugs 536 and it contains the solenoids 605 as shown in Figures 29 and 30. These solenoids 605 have cores 610 normally urged to the left by springs 611 but drawn to the right when the solenoids 605 are energized. The cores 610 are secured to rods 612 of brass or other non-magnetic material which extend through bushings 613 and to the edge of a supporting bar 614 which is secured to the lower front edge of the elevator 170a. When the solenoids 605 are energized the rods 613 project beyond the edge of the supporting bar 614 just far enough to engage the angle irons 535 so therefore the elevator 170a now lifts the door 527a and consequently also the door 541a.

One feature of the kiln of Figure 21 is illustrated in Figures 24, 26 and 27. As shown in Figure 26, a horizontal flue 620 extends from side to side of the kiln through the bricks above the tunnel 40a and similarly a horizontal flue 621 extends right across the kiln through the bricks above the tunnel 41a. Metal pipes 622 extend from the outside of the side wall 21a and the outside of the side wall 22a to these flues 620 and 621. As shown in Figure 24, these flues 620 and 621 are connected to longitudinal flues 625 and 626 and as shown in Figure 27 there are three flues 625 and three flues 626 but of course there might be more or less. These flues 625 and 626 end in downwardly extending passages 627 and 628 extending into the tunnels 40a and 41a respectively as indicated in Figure 24. These flues 625 and 626 are heated by the firing zones and the suction created by the chimney 115 draws air through these flues 625 and 626. This is preheated air which enters the preheating zone and furthermore supplies oxygen for the burning of combustible temporary binder in the ware being vitrified. I have found that these air preheating longitudinal flues 625 and 626 extending above the firing zones of the tunnels improve the efficiency of the kiln. The flues 116 and 116a and connections serve to back draught the tunnels 40, 41 and 40a, 41a respectively and especially in combination with the longitudinal flues 625 and 626 and connections. Thus the latter may provide most of the air for burning out the organic matter in the ware without over cooling the annealing zone by drawing air therethrough. For the chimneys 115 and 115a together with the inclination of the tunnels 40, 41, 40a and 41a set up suction to draw air the length of the tunnels, from the end of the annealing zone to the front of the preheating zone, but by opening the dampers such as 151, 152, 153 and 154 a back draught in the annealing zone is created and this back draught is adjustable. Thus may the tem-

perature of various parts of the annealing zone be controlled.

The elevator 170 is a transverse mover since it moves the batts transverse to the strokes of the rams and, so far as certain features of the invention are concerned, other transverse movers might be substituted. Any transverse mover will suffice to get batts in front of a ram for ramming into a tunnel.

It will thus be seen that there has been provided by this invention a tunnel kiln in which the various objects hereinabove set forth together with many thoroughly practical advantages are successfully achieved. As many possible embodiments might be made of the above invention and as many changes might be made in the embodiments above set forth, it is to be understood that all matter hereinbefore set forth or shown in the accompanying drawings is to be interpreted as illustrative and not in a limiting sense.

I claim:

1. A tunnel kiln comprising an elongated refractory structure having a pair of parallel tunnels one above the other, electrical rod resistors extending through said refractory structure from side to side in a plurality of banks there being at least one bank of rods extending transversely through each tunnel, a pair of batt supporting rods in each tunnel said batt supporting rods of each pair being parallel to each other and extending lengthwise of the tunnel, means to move refractory batts on said supporting rods through each of said tunnels, said tunnels being connected only by a passage at the locus of the banks of rod resistors.

2. A tunnel kiln according to claim 1 having a bank of rod resistors in the passage between the tunnels, said rods serving to heat the bottom of the upper tunnel and the top of the lower tunnel.

3. A tunnel kiln according to claim 2 having three banks of rod resistors on three levels, the bank of the lower level extending through the lower tunnel near the bottom thereof, the bank of the upper level extending through the upper tunnel near the top thereof, and the bank of the middle level extending through the passage between the tunnels and therefore serving to heat the bottom of the upper tunnel and the top of the lower tunnel.

4. A tunnel kiln comprising an elongated refractory structure having a pair of parallel tunnels, each tunnel having three zones, a preheating zone, a firing zone and an annealing zone, a pair of supporting rods parallel to each other in each tunnel and extending lengthwise of the tunnel for supporting refractory batts in each tunnel for movement in a continuous contiguous succession of batts through each tunnel, a ram at the entrance to the preheating zone of each tunnel to ram batts thereinto, electric heating means above the supporting rods in the firing zone of each tunnel, electric heating means below the supporting rods in the firing zone of each tunnel, the firing zones of the tunnels being connected only at the locus of the electric heating means and the electric heating means above the supporting rods of the lower tunnel being the electric heating means below the supporting rods of the upper tunnel.

5. A tunnel kiln according to claim 4 in which the several electric heating means are banks of electrical rod resistors.

6. A tunnel kiln comprising an elongated refractory structure having a pair of tunnels one above the other, each tunnel having a firing zone,

a pair of parallel lines of refractory rods extending on either side of each tunnel through the firing zone thereof whereby to support refractory batts in a contiguous succession of refractory batts in the firing zones, heating elements extending across each tunnel in the firing zone thereof in a bank above each pair of parallel lines of refractory rods, heating elements extending across each tunnel in the firing zone thereof in a bank below each pair of parallel lines of refractory rods, only the firing zones of the tunnels being connected by a passage and a bank of the aforesaid heating elements being located in said passage and being the bank below the rods in the upper tunnel and above the rods in the lower tunnel.

7. A tunnel kiln comprising an elongated structure of refractory material forming a tunnel, a preheating zone, a firing zone, and an annealing zone in said tunnel, electrical rod resistors extending across said tunnel in the firing zone, a door at the opening to the preheating zone, a door at the opening to the annealing zone, a chimney for said kiln connected to the tunnel near the door to the preheating zone, a flue from the annealing zone to said chimney, means at the exit end of the annealing zone adjustable to admit varying amounts of air into the tunnel and flues in the refractory structure of the firing zone connected at one end to the outside air and at the other end to the preheating zone.

8. A tunnel kiln and loading mechanism therefor comprising a refractory structure having a pair of parallel tunnels therein, electric heating means for each of said tunnels, there being an opening at each end of each tunnel, a ram in line with each tunnel and outside thereof, there being at least two of said rams and said rams being at the same end of the kiln, power means for moving each ram reciprocably, an endless loading conveyor outside of the kiln, means to move said loading conveyor in a given direction intermittently, transverse moving means reciprocably movable between three positions outside of said kiln, one position being adjacent said loading conveyor and in that position said transverse moving means being capable of receiving a batt or batts, an intermediate one of said positions being between one of said openings and one of

said rams and an extreme one of said positions being between the other of said openings and the other of said rams, means for moving said transverse moving means to and fro, means for stopping said transverse moving means in the intermediate position, and controlling means for causing said means to move said loading conveyor to move it thereby moving a batt or batts onto the transverse moving means, then to operate the means for moving the transverse moving means, then to operate the means for stopping the transverse moving means at the intermediate position, then to cause the power means to move the ram adjacent thereto thereby ramming the batt or batts into the adjacent tunnel, then to operate the means for moving the transverse moving means to move the latter back to the position adjacent the loading conveyor again operating the means to move the loading conveyor and causing the loading conveyor to move a batt or batts onto the transverse moving means again operating the means for moving said transverse moving means to cause it to move to its extreme position between the other of said openings and the other of said rams, then operating the power means for moving said last named ram to cause it to ram

a batt or batts into the other of said tunnels, then operating the means for moving the transverse moving means to cause it to return to adjacent the loading conveyor.

9. In a tunnel kiln as claimed in claim 8, the combination with the parts and features therein specified, of timer means modifying the controlling means to stop the sequence of operations for a given interval of time and operable to resume the sequence of operations at the end of said interval.

10. In a tunnel kiln as claimed in claim 9, the combination with the parts and features therein specified, of a pair of discharging conveyors one for each tunnel and located at the end of the kiln opposite the rams, power means for said discharging conveyors, and controlling means to cause said power means to operate when a batt or batts emerges from said tunnel onto a discharging conveyor.

11. In a tunnel kiln as claimed in claim 8, the combination with the parts and features therein specified, of a pair of discharging conveyors one for each tunnel and located at the end of the kiln opposite the rams, power means for said discharging conveyors, and controlling means to cause said power means to operate when a batt or batts emerges from said tunnel onto a discharging conveyor.

12. A tunnel kiln and loading mechanism therefor comprising a refractory structure having a pair of parallel tunnels therein one above the other, electric heating means for each of said tunnels, there being an opening at each end of each tunnel, a ram in line with each tunnel and outside thereof, there being at least two of said rams and said rams being at the same end of the kiln, power means for moving each ram reciprocably, an endless loading conveyor outside of the kiln, means to move said loading conveyor in a given direction intermittently, an elevator movable between three positions outside of said kiln, one position being adjacent said loading conveyor and in that position said elevator being capable of receiving a batt or batts, an intermediate one of said positions being between one of said openings and one of said rams and an extreme one of said positions being between the other of said openings and the other of said rams, means for moving said elevator, means for stopping said elevator in the intermediate position, and controlling means for causing said means to move said loading conveyor to move it thereby moving a batt or batts onto the elevator, then to operate the means for moving the elevator, then to operate the means for stopping the elevator at the intermediate position, then to cause the power means to move the ram adjacent there-

to thereby ramming the batt or batts into the adjacent tunnel, then to operate the means for moving the elevator to move the latter back to the position adjacent the loading conveyor again operating the means to move the loading conveyor and causing the loading conveyor to move a batt or batts onto the elevator again operating the means for moving the elevator to cause it to move to its extreme position between the other of said openings and the other of said rams, then operating the power means for moving said last named ram to cause it to ram a batt or batts into the other of said tunnels, then operating the means for moving the elevator to cause it to return to adjacent the loading conveyor.

15 13. In a tunnel kiln as claimed in claim 12, the combination with the parts and features therein specified, of timer means modifying the controlling means to stop the sequence of operations for a given interval of time and operable to resume the sequence of operations at the end of said interval.

20 14. In a tunnel kiln as claimed in claim 13, the combination with the parts and features therein specified, of a pair of discharging conveyors one for each tunnel and located at the end of the kiln opposite the rams, power means for said discharging conveyors, and controlling means to cause said power means to operate when a batt or batts emerges from said tunnel onto a discharging conveyor.

25 15. In a tunnel kiln as claimed in claim 12, the combination with the parts and features therein specified, of a pair of discharging conveyors one for each tunnel and located at the end of the kiln opposite the rams, power means for said discharging conveyors, and controlling means to cause said power means to operate when a batt or batts emerges from said tunnel onto a discharging conveyor.
